UNITED STATES PATENT OFFICE.

ISAAC E. SEXTON, OF WINCHESTER, MASSACHUSETTS.

JACKET-SECURING MEANS FOR JACKETED CANS.

Application filed July 9, 1925. Serial No. 42,457.

To all whom it may concern:

Be it known that I, ISAAC E. SEXTON, a citizen of the United States, residing at Winchester, in the county of Middlesex and State of Massachusetts, have invented new and useful Improvements in Jacket-Securing Means for Jacketed Cans, of which the following is a specification.

This invention relates to a sheet metal shipping can and to a jacket therefor, the can including a cylindrical body and a bottom offset inward from the lower end of the body to form a recess, the jacket including a cylindrical body member covering and secured to the can body, and a discoidal bottom member covering and secured to the can bottom and located within said recess, said jacket members being usually of wood.

The object of the invention is to provide improved means for securing the bottom member of the jacket to the can bottom, and at the same time protect said bottom member.

Of the accompanying drawings forming a part of this specification—

Figure 1 is a side view of a jacketed can provided with jacket bottom-securing means embodying the invention.

Figure 2 is an end view, on a larger scale, looking toward the bottom of the can, a portion being broken away.

Figure 3 is a section on line 3—3 of Figure 2.

Figure 4 is a section on line 4—4 of Figure 2.

Figure 5 is a fragmentary sectional view, showing a portion of the can without the jacket and securing means.

Figure 6 shows in perspective, the crossed strips in which my invention is embodied.

Figure 7 is a view similar to Figure 4, the body member of the jacket being omitted.

The same reference characters indicate the same parts in all of the figures.

In the drawings, 12 designates the cylindrical body, and 13 the bottom of a sheet metal shipping can of ordinary construction. The bottom is provided with a marginal flange 14 (Figure 5), U-shaped in cross section, forming an annular channel which receives the lower end of the body 12 and is secured thereto in the usual or any suitable manner, the flange forming the lower end of the can. The outer portion of the flange forms an upwardly facing shoulder 15 (Figure 5) on the periphery of the body and

adjacent to the lower end. This shoulder is utilized as an element of means for confining in place the crossed securing strips herein-after described.

The bottom 13 is offset from the lower end of the body, so that a recess is formed, receiving the bottom member of the jacket. 16 designates the body member of the jacket, this being a flexible sheet of wood bent around the body of the can and secured thereon by hoops 17. 18 designates the bottom member of the jacket, which is a wooden disc inserted in the bottom recess of the can, and covering the under side of the can bottom.

The bottom member 18 is secured in place by two crossed sheet metal strips 19 and 20. The strip 19 is in contact with the bottom member entirely across the latter, and is called the inner strip. The other or outer strip 20 contacts at its end portions with the jacket bottom member 18, and extends across and contacts with the midlength portion of the inner strip 19.

Each strip is provided at its opposite ends with upstanding ears 21, which are connected with the body of the strip by U-shaped necks 22, extending across the flange 14. The ears 21 are thin and are adapted to be forced into the crevice between the can body 12 and the body jacket member 16. This member is flexible and is held somewhat yieldingly against the can body by the hoops 17, so that the portions of the jacket member with which the ears contact are slightly bulged outward by the ears, as shown by Figure 2. The ears are provided with detents 23, adapted to engage the shoulder 15 when the ears have been forced to the limit between the can body and the jacket member 16. The engagement of the detents with the shoulder prevents the ears from being accidentally withdrawn. The detents 23 are preferably tongues integral with the ears and projecting from their inner sides, as shown by Figure 6.

After the cylindrical jacket member 16 has been secured by the hoops to the can body 12, the bottom jacket member 18 may be applied to the can bottom 13, and then secured by forcing the ears 21 of the inner strip 19 into the crevice between the can body and the jacket body member, until the strip bears on the bottom jacket member 18, the detents 23 at the same time engaging the shoulder 15. The outer strip 20 may

then be applied in position to extend across the midlength of the inner strip, and secured by forcing its ears into said crevice until the outer strip contacts with the inner strip, and the detents 23 engage the shoulder 15.

The strips are thus secured in position to secure the bottom jacket member and protect it to a considerable extent from injury by contact with external objects.

The inner strip 19 is preferably stiffened by longitudinal bosses 25, projecting from its under side. The bosses are interrupted to form a flat portion at the midlength of the strip, constituting a seat for the outer strip 20. I prefer to impart a channeled form to the outer strip, by providing it with continuous longitudinal inwardly projecting flanges 27, contacting with the midlength portion of the inner strip 19, as shown by Figure 3. The flanges stiffen the outer strip and increase its effective thickness, so that the under side of the strip is adapted to bear on a support on which the can rests.

It will be seen that the operation of applying the strips 19 and 20 is very simple and quickly performed, the operation involving only the driving of the ears 21 into the crevice between the can body and the body member of the jacket until the detents 23 engage the shoulder 15. The tension of the flexible jacket member 16 holds the detents in secure engagement with the shoulder.

35 The body member 16 of the jacket may be omitted, as indicated by Figure 7, and the ears 21 may be inserted in the crevice between the can body 12 and a hoop 17^a substituted for the lower hoop 17, the hoop 17^a being employed only to engage the ears and of smaller diameter than a hoop 17 formed to confine a jacket member against the can body.

45 The hoop 17^a constitutes an embodiment of means with which the can is provided for confining the ears 21 with their detents 23 in engagement with the shoulder 15.

The body jacket member 16 and the hoops 17 constitute another embodiment of means 50 for the same purpose.

I claim:

55 1. In a jacketed shipping can which includes a cylindrical body, and a bottom offset inward from the lower end of the body to form a recess, the body projecting below the bottom and having an external upwardly facing shoulder adjacent to and parallel with its lower end, the jacket including a discoidal body member contained in said recess and covering the can bottom; bottom-

member securing means comprising inner and outer crossed sheet metal strips, each having upstanding ears at its opposite ends provided with detents adapted to engage said shoulder, the inner strip contacting 65 with the bottom member, while the outer strip contacts with the central portion of the inner strip, the can being provided with means for confining the ears with their detents in engagement with the shoulder. 70

2. In a jacketed shipping can which includes a cylindrical body, and a bottom offset inward from the lower end of the body to form a recess, the body projecting below the bottom and having an external upwardly facing shoulder adjacent to and parallel with its lower end, the jacket including a discoidal body member contained in said recess and covering the can bottom; bottom-member securing means comprising inner 80 and outer crossed sheet metal strips, each having upstanding ears at its opposite ends provided with detents adapted to engage said shoulder, the inner strip contacting with the bottom member, while the outer 85 strip contacts with the central portion of the inner strip, the inner strip being provided with longitudinal outwardly projecting stiffening bosses, interrupted to form a flat seat at the midlength portion of the strip, for the midlength portion of the outer strip, the can being provided with means for confining the ears with their detents in engagement with the shoulder.

3. In a jacketed shipping can which includes a cylindrical body, and a bottom offset inward from the lower end of the body to form a recess, the body projecting below the bottom and having an external upwardly facing shoulder adjacent to and parallel with its lower end, the jacket including a discoidal body member contained in said recess and covering the can bottom; bottom-member securing means comprising inner and outer crossed sheet metal strips, each having upstanding ears at its opposite ends provided with detents adapted to engage said shoulder, the inner strip contacting with the bottom member, while the outer strip contacts with the central portion of the inner strip, the outer strip being provided with continuous longitudinal inwardly projecting stiffening flanges contacting at their midlength portions with the midlength portion of the inner strip, the can being provided 105 with means for confining the ears with their detents in engagement with the shoulder. 110

115 In testimony whereof I have affixed my signature.

ISAAC E. SEXTON,
